M. Garcia-Zamor(57) **CLAIM**The ornamental design for an arm sling, as shown and
described.

DESCRIPTION

FIG. 1 is a perspective view of an arm sling showing my new
design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.

The broken lines in FIGS. 1-7 represent environment and
are for illustrative purposes only and do not constitute part
of the claimed design.**1 Claim, 3 Drawing Sheets****US D561,902 S**
